UNITED STATES PATENT OFFICE

129,394

DESIGN FOR A COMBINED LATCH HANDLE AND ESCUTCHEON

Clare E. Hodgman, Chicago, Ill., assignor to Sears,
Roebuck and Co., Chicago, Ill., a corporation of
New York

Application March 8, 1941, Serial No. 99,421

Term of patent 7 years

To all whom it may concern:

Be it known that I, Clare E. Hodgman, a citizen of the United States, residing at Chicago, in the county of Cook and State of Illinois, have invented a new, original, and ornamental Design for a Combined Latch Handle and Escutcheon, of which the following is a specification, reference being had to the accompanying drawing, forming a part thereof.

Fig. 1 of the drawing is a perspective view of a

combined latch handle and escutcheon embodying my new design;

Fig. 2 is a diametrical section of the same, taken as indicated by the line 2—2 in Fig. 1; and Figs. 3 and 4 are sections, respectively, on lines 3—3 and 4—4 of Fig. 1.

I claim:

The ornamental design for a combined latch handle and escutcheon, as shown.

CLARE E. HODGMAN.
